UNITED STATES PATENT OFFICE

147,754

DESIGN FOR AN EARRING OR SIMILAR ARTICLE

Paul Kaufman, New York, N. Y.

Application August 22, 1946, Serial No. 132,753

Term of patent 3½ years

(Cl. D45—9)

To all whom it may concern:

Be it known that I, Paul Kaufman, a citizen of the United States, residing at New York, in the county of New York and State of New York, have invented a new, original, and ornamental Design for an Earring or Similar Article, of which the following is a specification, reference being had to the accompanying drawing, forming part thereof.

In the drawing:

Fig. 1 is a front view of an earring showing my new design; and
Fig. 2 is a side view thereof.

I claim:

The ornamental design for an earring or similar article, as shown.

PAUL KAUFMAN.
